UNITED STATES PATENT OFFICE.

ABRAHAM B. SNYDER, OF LOUISVILLE, OHIO.

RAILWAY-SIGNAL.

SPECIFICATION forming part of Letters Patent No. 291,545, dated January 8, 1884.

Application filed August 27, 1883. (No model.)

To all whom it may concern:

Be it known that I, ABRAHAM B. SNYDER, a citizen of the United States, residing at Louisville, in the county of Stark and State 5 of Ohio, have invented certain new and useful Improvements in Railway-Signals; and I do hereby declare that the following is a full, clear, and exact description of the same, reference being had to the annexed drawings, 10 making a part of this specification, and to the letters and figures of reference marked thereon, in which—

Figure 1 is a top view. Fig. 2 is a side view, and Fig. 3 is a transverse sectional view on line H H of Fig. 1.

The present invention has relation to railway-signals designed to be used at street-crossings; and its nature consists in the several parts and combination of parts hereinafter 20 set forth.

Similar letters of reference indicate corresponding parts in the drawings.

A represents the spring, which is of the form shown in Figs. 1 and 2, and should be made 25 of the best spring-steel, its normal form being as shown in Fig. 2, and is located at the side of the rail, and is so adjusted that its top or upper part will extend a short distance above the top of the rail, as shown in Fig. 2. One end 30 of this spring is firmly held to the cross-tie by means of screws or spikes, said end having a large flat surface to prevent said spring from moving laterally. The opposite end is firmly attached to the rod B by rivets or bolts. The 35 opposite end of the rod B is attached to the bottom or lower end of the signal-arm C by a rivet or bolt, and is attached so as to form a hinge or joint. The rod B is held in proper position by means of the boards D and blocks 40 E, said boards having a longitudinal recess which fits over a corresponding recess in the

blocks E, as shown in Fig. 3. The signal-arms C are fulcrumed to the segment F, as shown in Fig. 1, and are so arranged that they will be easily operated by means of the spring A 45 and rod B as a train passes over said spring. The signal-arms C should be held a short distance apart, which is done by means of a washer placed between said arms, as shown in Fig. 3, so that the movements of the arms C 50 will not interfere with each other. The top or upper ends of the signal-arms C are provided with the signals G, and may be of any desired form, and should be painted with some bright color, and one a different color from 55 the other. It will be seen that as a train of cars passes over the spring A said spring will be pressed down to a level with the top of the railway-rail, thereby forcing the end of said spring forward and causing the rod B to move 60 the signal G, and as soon as a wheel has passed said spring it will assume its normal position, thereby causing the signal to be waved by the wheels of a passing train, one of these springs being placed on each side of the street and at 65 a sufficient distance from the street to signal the approach of a train in time to prevent any accident.

Having now fully described my invention, what I claim as new, and desire to secure by 70 Letters Patent, is—

The boards D, provided with longitudinal recess, and the blocks E, having recess, in combination with the rod B and spring A, substantially as and for the purpose specified. 75

In testimony that I claim the above I have hereunto subscribed my name in presence of two witnesses.

ABRAHAM B. SNYDER.
